DEGENERATIVE AMPLIFIER

Bernardus W. v. Ingen Schenau, Eindhoven, Netherlands, assignor, by mesne assignments, to Radio Corporation of America, New York, N. Y., a corporation of Delaware

Application July 28, 1939, Serial No. 286,992
In Germany April 1, 1939

5 Claims. (Cl. 179—171)

The present invention relates to an amplifying system having negative feedback which acts on the input circuit of an amplifying tube comprising a directly heated cathode.

The known negative feedback, which is frequently utilized with indirectly heated amplifying tubes and with which the voltage fed back (and which voltage is derived from the output transformer of the amplifier) is supplied to a resistance in the cathode lead of the amplifying tube to the input circuit of which the negative feedback takes place, is unsuitable for systems comprising directly heated amplifying tubes. On the one hand, the resistance in the cathode lead would have to be of small value to avoid the heating current bringing about an excessive drop of voltage across the said resistance, while, on the other hand, the resistance would have to be large in order to avoid excessive damping of the output transformer by which the negative feedback voltage is supplied to the said resistance.

According to the present invention, this drawback is removed if the negative feedback voltage is supplied to the directly heated cathode of the amplifying tube on the input circuit of which the negative feedback is operative.

The invention will be more clearly understood by reference to the accompanying drawing which represents, by way of example, an amplifier negatively coupled back in this way.

The amplifier shown comprises two amplifying tubes 1 and 2 which are coupled with one another by means of a resistance-condenser coupling 3, 4, 5. The oscillations to be amplified are supplied to input terminals 6 and 7, and the amplified oscillations are taken from the secondary winding of an output transformer 8. The amplifying tubes 1 and 2 have directly heated cathodes which are supplied by a source of direct current (D. C.) voltage connected between terminals 9 and 10.

Negative feedback to the input circuit of the amplifying tube 1 is obtained by supplying a negative feedback voltage taken from the secondary winding of the output transformer to the cathode of the amplifying tube 1. To that end a portion 11 of the secondary winding of the output transformer is connected in series with the cathode of the amplifying tube 1 so that an alternating voltage, dependent upon the voltage induced in the portion 11 of the secondary winding of the output transformer, is applied to the cathode of the amplifying tube 1. Between the grid and the cathode an alternating voltage is thus set up which is in counter-phase with the voltage to be

amplified and which is supplied by the terminals 6 and 7 to the grid, so that negative feedback is obtained.

The resistance of the filament of the amplifying tube 1 is comparatively high (i. e. of the order of magnitude of 30 ohms, and, therefore, brings about only slight damping of the portion 11 of the secondary winding of the output transformer, which portion is connected in parallel therewith, 10 more particularly if only part of the secondary winding is included in the heating circuit of tube 1, as is the case in the system shown. Furthermore, in the usual output transformers the D. C. resistance of the secondary winding is small so 15 that the heating current of the tube 1 does not produce an appreciable voltage drop across this winding.

Impedances may be incorporated in the negative feedback circuit in order to influence the frequency characteristic of the amplifier. Such an impedance, consisting of the parallel connection of an inductance coil 12, a condenser 13 and a resistance 14, is represented in the drawing. This parallel connection is tuned in such manner 25 that it constitutes a high impedance for high frequencies with the result that for high frequencies the negative feedback decreases, and consequently the amplification increases for these frequencies.

30. What is claimed is:
  1. In combination with a tube having at least a grid, cathode, and output electrode, means for impressing signals between the grid and cathode, means for directly heating the cathode, a second tube, provided with input and output electrodes, having its input electrodes coupled to the first tube output electrode, an output transformer coupled to the output electrodes of the second tube, and at least a portion of the transformer secondary in circuit with said heating means.
  2. In combination with a tube having at least a grid, cathode, and output electrode, means for impressing signals between the grid and cathode, means for directly heating the cathode, a second tube, provided with input and output electrodes, having its input electrodes coupled to the first tube output electrode, an output transformer coupled to the output electrodes of the second tube, and at least a portion of the transformer secondary in circuit with said heating means arranged to degeneratively feed back signal voltage to said grid and cathode.
  3. In combination with a tube having at least a grid, cathode, and output electrode, means for impressing signals between the grid and cathode,
- 55

means for directly heating the cathode, a second tube, provided with input and output electrodes, having its input electrodes coupled to the first tube output electrode, an output transformer coupled to the output electrodes of the second tube, and at least a portion of the transformer secondary in circuit with said heating means, and frequency-discrimination means in circuit with said heating means.

4. In a signal amplifier network having a plurality of tubes coupled in cascade, at least one tube having a cathode in direct circuit with a heating current source, an output circuit connected to a later one of the tubes, at least a portion of said output circuit being included solely in

10 the said heating circuit whereby signals are degeneratively applied to said one tube input circuit.

5. In a signal amplifier network having a plurality of tubes coupled in cascade, at least one tube having a cathode in direct circuit with a heating current source, an output circuit connected to a later one of the tubes, at least a portion of said output circuit being included solely in the said heating circuit whereby signals are degeneratively applied to said one tube input circuit, said output circuit comprising a transformer, and said portion being a section of the transformer secondary.
